UNITED STATES PATENT OFFICE

CHARLES HENRI BICHLER, OF PARIS, FRANCE

DEVICE FOR THE PREVENTION OF BACK-FIRE TO THE CARBURETORS FOR INTERNAL-COMBUSTION ENGINES AND FOR OTHER PURPOSES

Application filed March 16, 1929, Serial No. 347,719, and in France July 23, 1928.

The present invention relates to a device for the prevention of back-fire to the carburetor, for internal combustion engines and for other purposes.

5 It has been already proposed, for the prevention of back-fire to the carburetor in internal combustion engines, to dispose in the suction conduit suitable plates which are properly spaced apart and thus form a set 10 which allows the free circulation of the fuel mixture to the engine but prevents all return of the flames to the carburetor. The set or plates is disposed in the admission conduit at a suitable point between the carburetor and the engine.

The present invention has for its object a special arrangement of the said plates for the prevention of backfire, in which the sets of plates have a square, rectangular, polygonal, circular or other cross section and are disposed in conduits or portions of conduits of corresponding form situated between the carburetor and the engine, or even before the carburetor, said plates being assembled by 20 connecting members which hold them properly spaced apart and are disposed at or near the edges of the plates, thus leaving the middle part of the plates entirely free. In this manner, the gas will have a free circulation, avoiding obstruction to the fuel gas in the admission conduit. Means are also provided for heating the fuel gas preferably in an adjustable manner disposed before the set of plates or extending through said 30 plates whereby the engine will be properly supplied in all cases.

In the accompanying drawing which represents various embodiments of the invention;

40 Figs. 1 and 2 are respectively an elevational view with parts broken away, and an end view with partial cross-section, of a square section conduit containing a set of plates of square section.

45 Figs. 3 and 4 are respectively an end view and an elevational view of a set of plates adapted to be placed in a cylindrical conduit.

Fig. 5 is a set of plates fitting upon the outlet of the carburetor in the case in which

space is wanting at the end of the carburetor to contain a normal set of plates.

Figs. 6, 7 and 8 are respectively an elevational view, a left hand end view and a right hand end view, of a modification comprising partially movable flanges.

55 Fig. 9 is a partial section of a modified form of the device shown in Figures 1 and 2, the section in Figure 9 being made according to two different half planes whereof one passes 60 through the heating tube and the other at the outside of the said tube.

Fig. 10 is a perspective view of one of the plates shown in Figure 9.

Fig. 11 is a detail of the device holding 65 the set of plates according to Figure 9.

Fig. 12 is a general view showing the circulation of the heating fluid used for the admission conduit.

In the form of construction shown in Figures 1 and 2, there is mounted upon the usual fuel feed pipe of the internal combustion engine a conduit 1 of square cross-section, provided with the connecting flanges 2 of the known form by which the said conduit can 70 be mounted upon the pipes leading respectively to the carburetor and the cylinder head of the engine.

In the interior of the said conduit 1 are disposed the plates 3 in suitable number, 80 these being held at the proper distance apart by spacing bolts 4 which as shown chiefly in Fig. 2 are disposed near the edges of the said plates, leaving the middle part of the conduit free.

85 By this arrangement, the gas stream will circulate freely in the middle part of the set of plates without obstruction from the said spacing bolts, and since the central part of the gas stream will normally travel at the greatest speed, the obstruction offered to the circulation of the gas in the conduit containing the spaced plates will have a minimum effect in opposing the circulation of the gas from the carburetor to the engine. On the 90 other hand, since the said plates form a homogeneous set, they will provide an adequate cooling surface for preventing all access of the flame to the carburetor, the cooling surface being increased by the use of the square 95

cross-section for the said conduit, whereby the width of the said plates can be much increased.

To further provide for the proper space in the central part of such conduits in the case of conduits of circular cross-section containing cylindrical sets of plates, the said plates (Fig. 3) are assembled by spacing bolts 5 which are situated at the proper distance on either side of the longitudinal axis of the system, and whose ends are secured to the plates 6 (Fig. 3) situated at a suitable distance from the longitudinal axis. The said plates 6 are in turn secured to the end plates 15 of the set by the spacing bolts 7 which are provided in suitable member and are properly distributed along the height of the said plates.

In Fig. 9, the partial half-section on the right shows a tube 17 connecting the opposite plates 18 of the heating jacket, thus raising the temperature of the gas mixture leaving the carburetor, in order to prevent all formation of frost upon the plates 9. As shown in Fig. 10, each of the plates 9 has at the middle of its lower part a notch 19 fitting upon the tube 17 of suitable cross-section in order to assure the proper radiation in the plates 9, of the heat supplied by the tube 17. Instead of maintaining the set of plates in position by screws shown at 20 in Figure 1, there is preferably disposed on either side of the set of plates a tongue 21 (Fig. 11) having a nip 22 engaging in perforations in the end plates of the set, as shown on the left of Fig. 9. At the bottom of each tongue 21 is a flange 23, which in the assembled position will be engaged in a recess 24 of the corresponding flange 2.

To further the heating of the device for the prevention of frost, there is disposed on the channel 25 for the circulation of the water for the heating of the usual conduits, a main transverse pipe 26 (Fig. 12) connecting the upper ends of the jacket serving to heat the conduits 27—28 supplying the heating water (or other fluid), to the plates 18 of Figure 9. The water which has circulated in said plates will then issue through the pipes 29—30 (Fig. 12) in order to heat the outlet of the carburetors 31—32.

To reduce the heating of the conduits 27—28 at will, the device comprises a by-pass 33 starting from the conduit 25 and communicating by a transverse tube 34 with the pipes 29—30 which supply heating water to the carburetors 31—32.

The heating tube 17 provided in the apparatus may have any desired height according to the temperature to which the plates 9 are to be heated. The said tube 17 may have the same height as the plates 9, and if desired, this tube can be used as a separating partition, dividing into two sections each of the conduits 27—28 containing the said plates 9.

In this case, the said plates may be disposed in guides provided in the lateral face of the tube 17 and also in the walls 17 of the said conduit, thus dispensing with any other retaining device.

The heating is preferably rendered adjustable by providing at a suitable point of the heating circuit 25—26—33—34, one or more cocks or the like which permit to determine with all necessary precision the amount of the water (or other) circulation for heating purposes in the usual conduits and also in the conduit containing the plates or blades 27—28, said parts being provided with suitable controlling means placed within the driver's reach. The said heating jacket, instead of being disposed as shown in Figures 1 and 9, may extend as far as the most restricted section of the flange 2, and herein the transverse heating tube 17 may be eliminated.

In the construction shown in Figure 5 which represents a very short conduit in which there is not sufficient room to dispose the set of plates, the said plates 9 are herein disposed mixing chamber 8 included in a discharge conduit of the carburetor, whose casing 10 is held in position by the screws 11. The plates replace the venturi shown in dotted lines.

To reduce the size of the apparatus, one end of the set of plates is cut out at 12 in order to fit upon the sprayer 13 of the carburetor.

It is also feasible to leave the usual venturi in the casing 10, and it may occupy the lower part of said casing, which herein will contain no plates, or the usual disposition may be employed in which the said plates will have a suitable shape to conform to the configuration of the Venturi wall.

Figs. 6 to 8 show an arrangement adapted to reduce the obstruction to the gas flow which is caused by the said plates, and herein one part of the set of plates is fixed and the other part movable.

The fixed part (Figs. 6 and 7) comprises plates 15 which are spaced apart by double the distance which is recognized as necessary to extinguish the flames, this distance being increased by the thickness of a plate.

The set of stationary plates 15 carries an axle 13 (Figs. 6 and 8) to which is pivoted a second set of plates 14, held together by cross-bolts 16 and bevelled at 17 (Fig. 8) to enable their release, when pivoting, from the said stationary plates 15, the whole device being mounted in a conduit not shown.

The movable plates 14 are spaced apart by the same distance as the stationary plates 15 and are disposed in the respective spaces between the latter, as shown chiefly in Fig. 8.

During the normal functioning of the engine, whose suction conduit contains the

sets 14 and 15, the gas from the carburetor circulating in the direction of the arrow (Fig. 6) will drive the movable set 14 into the position shown in the dot-and-dash lines, and thus 5 there will be no obstacle to the gas flow through the device.

In the case of back fire to the carburetor, that is, in the contrary direction to the arrow, the said movable set 14, which is no longer 10 driven back by the suction gas, will fall by its own weight into the position shown in the full lines, this action being furthered by the 15 force of the ignited gas circulating in the contrary direction to the arrow, and in consequence 15 the sets 14—15 will have the relative position shown in Fig. 8, in which they now form a single set whose plates have the proper spacing to obstruct the ignited gas, whereby the carburetor will be well protected from the 20 flames.

The sets formed by the plates 14 and the plates 15 may be placed in any position whether vertical, horizontal or inclined, although the vertical position is preferable. 25 The movable set 14 might also be made slideable with reference to the fixed set 15.

The fixed set and the movable set of plates may be given any suitable shape, depending upon the form of the conduits in which they 30 are disposed.

In the various constructions herein represented, the sets of plates may be disposed not only between the carburetor and the engine, but also in front of the carburetor and upon 35 the air intake conduit. It is preferable to combine these two arrangements in such manner as to prevent all access of flames not only to the carburetor but also to any point of the engine admission piping, whereby all danger 40 from this cause will be obviated.

The said invention is adapted for the prevention of back-fire to the carburetor in all types of internal combustion engines whether for air craft or for other uses, and more generally, in all cases in which a fuel mixture circulates in a conduit.

What I claim is:

1. A device for preventing back fire to the carburetor, for internal combustion engines 50 and for other uses which comprises a special disposition of the sets of anti-back-fire plates, in which the sets of plates whose cross-section is square, rectangular, polygonal, circular or the like, which are disposed in conduits or 55 portions of conduits of corresponding form, mounted between the carburetor and the engine, or even in front of the carburetor, are held together by connecting means, which hold them apart at a suitable relative distance, and which are disposed at the edges or near the edges of the said plates, while 60 leaving the middle part of the sets entirely free, thus affording a freedom of passage as great as possible for the fuel mixture, in order to reduce as completely as possible the 65

obstruction to said fuel mixture in the admission conduit, an arrangement being provided to permit any desired heating, preferably adjustable, of the fuel mixture, either in front of the set of plates or across the set 70 of plates, in such manner as to assure in all cases the proper feed to the engine.

2. A form of construction of the device according to claim 1, in which the plates forming the sets of plates are mounted in the discharge conduit of the carburetor in the place usually occupied by the venturi of said carburetor in such manner as to assure an effective protection of the carburetor against the return of the flames, even when the suction conduit of the engine is too short to contain a set of the usual anti-back-fire plates, and the venturi of the carburetor may also have placed upon it the said set of plates, in such manner as to reduce the size. 75

3. A modification comprising the combination of two sets of plates disposed along the length of the admission conduit, the strips or plates of one set being stationary and sufficiently spaced apart to allow the free flow of the suction gas, whilst the strips or plates of the second set, which are parallel to the first and have the same spacing are interposed between the plates of the first set and are movable with reference to these latter in order to prevent in a practically complete manner all obstruction to the suction gas of the engine, while effectively preventing all travel of the ignited gas. 80

In testimony whereof I have hereunto set 100 my hand at Paris this fifth day of March, 1929.
